UNITED STATES PATENT OFFICE.

FRANCIS C. MASON, OF GRAND RAPIDS, MICHIGAN, ASSIGNOR TO BISSELL CARPET SWEEPER COMPANY, OF GRAND RAPIDS, MICHIGAN, A CORPORATION OF MICHIGAN.

BALL-BEARING FOR CARPET-SWEEPERS.

No. 881,603.

Specification of Letters Patent. Patented March 10, 1908.

Application filed February 19, 1907. Serial No. 358,314.

To all whom it may concern:

Be it known that I, FRANCIS C. MASON, a citizen of the United States of America, residing at Grand Rapids, in the county of Kent and State of Michigan, have invented certain new and useful Improvements in Ball-Bearings for Carpet-Sweepers; and I do hereby declare the following to be a full, clear, and exact description of the invention, such 10 as will enable others skilled in the art to which it appertains to make and use the same.

My invention relates to improvements in carpet sweepers and more particularly to the 15 bearings of the brush shaft therein, and its object is to provide easy running, dust proof bearings for the same; to prevent strings and the like from winding into the bearings of the same; and to provide the device with various 20 new and useful features hereinafter more fully described and particularly pointed out in the claims.

My invention resides in the combination and arrangement with the brush shaft of a 25 carpet sweeper, and the flexible end guards of the same; of a cup-shaped guard, a shouldered pin secured to the guard bar, together with a cup, a cone and balls in the cup together with an annular retaining cap attached to the cup and when so assembled inserted in the respective ends of the brush shaft to co-act with said pins and the flexible bars, whereby an easy running and durable 30 bearing is produced for said brush shaft 35 adapted to support the shaft rotatively in place, and also adapted to furnish thrust bearings to receive the thrust due to the flexibility of the end guards, and dust strings and the like are prevented from getting into the 40 bearings or wound around the pin.

Referring to the accompanying drawings, Figure 1 is an end elevation of a carpet sweeper provided with my device with parts omitted. Fig. 2, a plan view of one end of 45 the same; Fig. 3, an enlarged detail of the ends of the brush shaft partially in section through the axis thereof; and Figs. 4, 5, 6, and 7 details of the various parts 11, 10, 12 and 5 respectively.

Like numbers refer to like parts in all of 50 the figures.

1 represents a carpet sweeper case; 2 the horizontally flexible end guards of the same, in which are inserted pins 3 projecting inward 55 horizontally opposite the axis of the brush

shaft, said pins having shoulders 14 near their inner ends to engage the outer face of the cones 12 and having their inner ends detachably inserted in axial openings in said cones.

4; 4 represent the pulleys on the respective ends of the brush shaft, each being provided with an annular recess 6 to receive the rim of a cup-shaped guard 5 secured to the bars 2 by the pins 3 and non-rotative thereon.

7 are the supporting and driving wheels which engage the pulleys 4 and rotate the brush shaft 9. Cups 11 are inserted in the respective ends of the brush shaft, which cups are provided with caps 10 provided with marginal flanges engaging the margins of the cups and thus attached thereto to retain the contents thereof and each cap is provided with an axial opening through which the pin 3 extends. These cups and caps with the cones and the circular series of balls 13 are permanently assembled and in this condition can be conveniently treated as a unitary structure and inserted in the ends of the brush shaft after which the brush shaft is placed in position by springing the guard bars 2 outward sufficiently to permit the pin to enter the cap and cone. The flexibility of the bars 2 tends to press the pins inward and thus crowd the cones toward the bottom of the cups, which prevents all looseness and rattling. The brush shaft is supported and freely rotative upon the balls and the guard 5 effectually excludes dust and grit from the 75 bearings and also prevents winding of strings or the like around the pins.

What I claim is:

1. An improved ball bearing for the brush shaft of a carpet sweeper, comprising a cup, a circular series of balls in the cup, a retaining cap having a flange engaging the periphery of the cup and attached thereto and a central opening for the pin, a cone loose in the cup and retained therein by the cap a pin extending through the opening in the cap and engaging the cone, and means for supporting the pin.

2. A ball bearing for the brush shaft of a carpet sweeper, comprising a cup, a circular series of balls in the cup, a cone loose in the cup and engaging the balls and also having an axial opening, a retaining cap having a flange engaging the rim of the cup and attached thereto, and also having a central opening to receive the pin, and a pin extend-

ing through said opening and engaging the cone.

3. An improved ball bearing for the brush shaft of a carpet sweeper, comprising a shaft, 5 cups inserted in the respective ends of the shaft, a circular series of balls in each cup, a cone loose in each cup and engaging the balls and also having an axial opening, a cap on each cup and having a flange engaging the 10 rim of the cup and attached thereto and also having a central opening in line with the

opening of the cone, opposing flexible supporting bars, and pins supported by the bars and inserted in the openings of the caps and cones, and also having shoulders engaging 15 the outer surfaces of the cones.

In testimony whereof I affix my signature in presence of two witnesses.

FRANCIS C. MASON.
